UNITED STATES PATENT OFFICE

98,732

DESIGN FOR A COMBINED TELEPHONE BASE AND PAD HOLDER

Leo A. Meltzer, Seattle, Wash.

Application April 12, 1935, Serial No. 56,346

Term of patent 14 years

To all whom it may concern:

Be it known that I, Leo A. Meltzer, a citizen of the United States, residing at Seattle, in the county of King and State of Washington, have invented a new, original, and ornamental Design for a Combined Telephone Base and Pad Holder, of which the following is a specification, reference being had to the accompanying drawing, forming part thereof.

ure 2 is a top perspective view of a combined telephone base and pad holder, showing my new design.

I claim:

The ornamental design for a combined telephone base and pad holder, as shown.

Signed at Seattle, King County, Washington, this 6th day of April, 1935.

LEO A. MELTZER.
